UNITED STATES PATENT OFFICE.

LOUIS E. TRACHSEL, OF ST. JOSEPH, MISSOURI, ASSIGNOR TO THE KING MANUFACTURING COMPANY, OF ST. JOSEPH, MISSOURI, A CORPORATION OF MISSOURI.

STORING DEVICE.

Application filed May 1, 1922. Serial No. 557,792.

To all whom it may concern:

Be it known that I, LOUIS E. TRACHSEL, a citizen of the United States, residing at St. Joseph, in the county of Buchanan and State 5 of Missouri, have invented certain new and useful Improvements in Storing Devices; and I do declare the following to be a full, clear, and exact description of the invention, such as will enable others skilled in the art 10 to which it appertains to make and use the same, reference being had to the accompanying drawings, and to the figures of reference marked thereon, which form a part of this specification.

15 This invention relates to a hose storing device which is adapted to normally store hose within a housing to prevent deterioration by the elements.

For example, air hose used around motor 20 vehicle service stations is liable to rapidly deteriorate as well as present an unsightly appearance if it is permitted to lie around upon the ground.

I have provided means whereby the hose 25 will be normally retracted within the housing and supported upon a reel which will readily unwind to play out the hose when it is desired to inflate tires and as soon as the hose is released, the reel will be effective in 30 causing the hose to be wound and retracted within the housing.

The invention contemplates certain novel details of construction and combinations of parts, all of which will be apparent by reference to the following description in connection with the accompanying drawings, in 35 which

Fig. 1 is a view partly in elevation and partly in section of a hose protector and 40 reel constructed in accordance with my invention.

Fig. 2 is a cross sectional view on the line 2-2 of Fig. 1, and

Fig. 3 is a detail perspective view of the 45 reel, showing the manner of attaching the hose to the axle thereof.

The reference numeral 1 designates a housing which is shown as an ornamental hollow post, at the top of which may be supported a lamp 2 of proper configuration, the specific construction of the lamp forming no part of the present invention.

The hollow post or casing may rest upon a suitable foundation 3 and enclose the operating parts of the storing mechanism.

Embedded in the foundation 3 is a pocket comprising a casting 4 extending slightly above the surface of the foundation and provided with edge flanges 5 and 6, upon which are mounted bearing standards 7 and 8, provided with anti-friction bearings 9 and 10, in which are mounted the ends 11 and 12 of a horizontal shaft 13, the shaft being adapted to rotate about its axis in the bearings 9 and 10.

Integral with the shaft 13 is a drum 14, having parallel flanges 15 and 16 spaced apart a distance substantially equal to the diameter of the flexible connection which is adapted to be wound thereon, thereby forming a relatively narrow groove 17 to receive the chain or flexible connection 18, which passes around the pulley 19 mounted on a shaft 20 at the upper portion of the post 1 and which is looped, as at 21, by fastening 75 its end 22 to an anchor 23, the loop carrying a weight 24 having a pulley or idler 25, in the groove of which is received the loop portion of the flexible connection 18. The purpose of making the groove 17 relatively narrow or approximately the diameter of the flexible connection 18 which, in the present instance, is shown as a chain, is to wind the flexible connection in a series of coils, one upon the other so that the diameter of the 80 wound portion of the chain will rapidly increase, that is, progressively increase with each complete wrap or winding, as will be fully explained hereinafter.

Fastened to the drum 14 is a hose drum 90 consisting of two plates 26 and 27, which are bolted to the drum 14 by the bolts 28, the plates 26 and 27 being spaced apart by the spacing ring 29, through which the bolts also pass, as will be clearly seen in Fig. 3. 95 The plate 27 is provided with a segmental slot 30, through which the hose 31 projects as it is extended from the space between the plates 26 and 27, the slot permitting a bend on a relatively wide angle so that there will 100 be no sharp turns in the hose which is fastened to the outstanding coupling 32, capped or screwed into the hollow portion 33 of the shaft 13.

The hollow end 3 is connected to a supply 105 pipe 34 by a suitable connection, shown as a stuffing box 35 and a flexible hose 36, the connection provided by the hose 36 being for the purpose of taking off the strain from the end 33 of the shaft 13 and to permit vi- 110

bration without breaking the connections. The stuffing box connection 35 can be of any appropriate construction, permitting the pipe 13' at the end of the shaft to rotate 5 within it.

The space between the plates 26 and 27 will preferably be approximately equal to the diameter of the hose to be wound upon the hose reel so that the diameter of the 10 wound coil will increase progressively with each turn of the shaft 13, and this will be accomplished while the diameter of the coil on the drum 14 is progressively decreasing, and vice versa, as will be explained herein- 15 after.

The weight 24 is heavy enough to cause the shaft 13 to normally have a winding tendency so that the hose will be wound upon the hose reel. The weight 24 can be 20 a sectional weight having secured to its upper portion a lower portion 37 by the screw 38 so that the intermediate washers 39 can be reduced or multiplied in number to provide the proper balance.

25 The hose nozzle 40 will normally project through an opening 41 having anti-friction rollers 42 and 43 at its edges.

The weight will normally wind the hose upon its reel by unwinding the chain 18. 30 When it is desired to use the hose, the nozzle is grasped so that the hose can be paid out through the opening 41. This will cause the chain 18 to wind upon the reel 14 while the hose is unwinding. Since the chain is 35 arranged in a loop, a considerable length of chain may be confined within a relatively small space because the length of chain can be multiplied within the stand by passing it over the pulley 19, about the weight pulley 25 and fastening it to the anchor 23. As the hose is pulled out and the chain is wound 40 layer upon layer in the narrow slot 17, the periphery of the coil will be moving further and further from the center of the shaft 13 so that the leverage on the drum 14 will be 45 increasing in proportion to the amount of hose being paid out. Therefore, when practically all of the hose has been paid out, the diameter of the chain coil will be at its maximum. This is an important feature 50 because when a comparatively large part of the hose is paid out through the opening 41, it will require more energy to wind it on its reel than when only a small portion is paid out. Therefore, when the hose is 55 practically off the reel and the diameter of the chain coil about its pulley is greatest, it is obvious that the maximum leverage will be provided for the greatest amount of hose.

60 As the hose begins to wind and less effort is required to wind it on its drum, the diameter of the chain coil will be progressively decreasing. Therefore, the hose will be wound upon its reel at a substantially uniform rate of speed.

It is obvious, of course, that the hose is at all times supplied with air through the medium of the pipe 34, which may be connected to a compressed air tank or in the case of liquids, to a liquid tank under pressure so 70 that there will be an available supply at all times ready to discharge from the nozzle 40, the nozzle being of the usual type provided with a valve which may readily discharge into the tire or into the vessel to receive the 75 fluid supply.

By means of the stuffing box 35 and its connections, the shaft 13 may rotate without permitting the escape of air between the pipe 34 and the hose. The construction of 80 the shaft 13 and its drum 14 is preferably integral so that they may be cast together and thereby facilitate the assembly of the parts, the drum 14 affording an efficient supporting bracket for the hose reel consisting 85 of the plates 26 and 27.

It will be apparent, of course, that the housing or hollow post 1 may partake of any appropriate construction but for the sake of appearances, it is recommended that 90 the post be made ornamental.

Attention is also called to the fact that the hose 31 can pass through the slot 30 at an easy angle so that there will be no sharp bends in the hose which would tend to wear 95 or cut or break the same during the operation of winding and unwinding it.

What I claim and desire to secure by Letters Patent is:

1. In combination a housing, a rotatable shaft having a ported chamber, means for supplying fluid to said chamber, a flexible hose having connection with said chamber, a hose drum in fixed relation to and rotatable with said shaft and having a deep groove of a width substantially equal to the diameter of the hose and in which the hose is wound in single, superimposed convolutions, a second drum also fixed on the shaft and having a deep groove, a pulley rotatable in the housing, a flexible, looped connection having one end fixed to the housing and the other end fixed in the groove of the second drum, a pulley suspended in the loop of said connection, and a weight suspended from said pulley, the width of the flexible connection being substantially equal to that of the drum to which it is connected, the connection and hose being wound reversely on their drums in single coils of proportionately increasing and decreasing diameters respectively for the purpose set forth.

2. In combination, a housing, a rotatable shaft having a ported chamber, means for supplying fluid to said chamber, a drum rigid on said shaft and having a deep peripheral groove, a second drum comprising inner and outer plates and a spacing ring, the outer plate having an arcuate slot, means extending through the plates and 120

ring into the side of the first drum to attach the second drum rigidly to the first, a pulley suspended in the housing, a flexible looped connection run over said pulley and having its ends attached to the housing and the first named drum respectively, a weighted pulley suspended from the looped part of said connection, a hose, having one end mounted on said shaft, communicating with said ported chamber and run through the 10 slot in said outer drum plate, the flexible connections and hose being wound oppositely in single convolutions in their respective drums, substantially as and for the purpose set forth.

In testimony whereof I affix my signature.

LOUIS E. TRACHSEL.
